UNITED STATES PATENT OFFICE

99,671

DESIGN FOR A ROLL OR SIMILAR ARTICLE

Patrick J. Brennan, York, Pa., assignor of one-half to Edw. Fox Baking Co., Inc., York, Pa., a corporation of Pennsylvania

Application March 24, 1936, Serial No. 61,754

Term of patent 14 years

To all whom it may concern:

Be it known that I, Patrick J. Brennan, a citizen of the United States, residing in York, York County, Pennsylvania, have invented a new, original, and ornamental Design for a Roll or Similar Article, of which the following is a specification, reference being had to the accompanying drawing, forming part thereof, in which:

Figure 1 is a plan view, and Fig. 2 is a rear elevation of the roll or similar article showing my design.

I claim:

The ornamental design for a roll or similar article, substantially as shown.

PATRICK J. BRENNAN.
